17 Claims. (Cl. 204—188)

This invention relates to the electrical treatment of dispersions for the purpose of removing or facilitating the removal of dispersed particles existing therein.

In conventional electric treaters, a dispersion is subjected to a high-voltage electrostatic field as the dispersion passes through the treating space between a pair of electrodes. The dispersion may comprise an external or continuous phase of a relatively electrically nonconducting liquid such as an oil, a polymer, or the like, and an internal or dispersed phase of relatively electrically conducting particles which may be in liquid or solid form. Typically the particles may be water, brine, chemically modified water, acid sludge, products resulting from the reaction of a chemical agent with some dissolved or dispersed component of the oil, solid or gel particles, salt crystals, dirt, oxide, etc.

Such dispersions are referred to herein as hydrocarbon-continuous dispersions comprising a hydrocarbon phase with dispersed particles therein. During the electric treatment the dispersed particles are joined or brought together by the field, as by being coalesced or agglomerated into larger particles which are partially or wholly separated from the continuous phase by settling within the treating space or in a zone communicating therewith. In some instances a portion or all of the dispersed particles will be electrophoresed by the field to deposit on one or both electrode surfaces and thereby join with other particles as when treating dispersions of low dispersed-phase content in a high-voltage unidirectional electric field.

In the conventional electric treater, the electrostatic field between the electrodes is established by connecting an external electric power source to the electrodes, with the associated problems of electric power supply control and regulation, wiring, feed-through insulation, and shock hazard. It is an object of the present invention to provide a new and improved electric treater and method of treatment which eliminate the requirement for external power supply connections to the electrodes.

It is a particular object of the invention to provide a method of electrically treating a dispersion including the steps of producing an electrically charged fluid stream, flowing the charged stream into contact with an electrode to induce a charge thereon and establish an electrostatic field in the space between two electrodes, and delivering a stream of the dispersion to the space between the electrodes for electric treatment therein. The treated dispersion can be partially separated in such treating space or it can be withdrawn therefrom and supplied to a settling space or to additional equipment that will further treat the effluent dispersion and separate it. The further treatment may be by electrical, chemical or centrifugal action or by a combination thereof and will result in further separation of the phase materials. A further object is to provide such a method in which the stream of dispersion to be treated is utilized as the electrically charged stream for inducing the charge on the one electrode. Another object is to provide a method in which a separate fluid stream is used for the electrically charging operation with the dispersion stream being introduced directly into the space between the electrodes.

It is an object of the invention to provide a new and 70 novel apparatus for electrically treating a dispersion including means for generating an electrical charge in a

2

stream of fluid to produce a charged stream, first and second spaced electrodes defining a treating space therebetween, means for mounting the first electrode electrically insulated from the second electrode, means for flowing the charged stream of fluid into contact with the first electrode to induce a charge thereon and establish an electrostatic field in the treating space, and means for delivering a stream of the dispersion to the treating space for electrical treatment therein. The effluent may be settled or treated as mentioned above. A further object of the invention is to provide such an apparatus including a charge generating element mounted within the treater for generating an electrical charge in a fluid stream directed therethrough.

It is a particular object of the invention to provide an electric treater of the type referred to above including means for flowing the dispersion stream through the charge generating means and then into contact with an electrode or into contact with some element electrically connected thereto for inducing a charge on the electrode, with the dispersion stream being then directed into the space between this and another electrode for treatment. Another object is to provide an alternative form of the treater including means for circulating a charging stream between the charge generating means and the electrode, the charging stream being maintained separate from the dispersion stream thereby permitting the use of different materials and flow rates for charging and treatment.

A further object is to provide a method and apparatus 30 in which an electrically insulated electrode is charged by contacting one portion or surface thereof with a charging liquid, another portion or surface thereof bounding a treating space in which a dispersion is treated. A further object is to flow the charging liquid in contact with such one portion at such rate that a substantial portion or all of its charge is imparted to the insulated electrode. The charge on the electrode tends to dissipate into the dispersion at a rate dependent largely on the electrical resistivity of the latter. It is an object to control or correlate the rate of flow of the charging liquid and the resistivity of the dispersion to maintain the electrode at a potential sufficient to treat the dispersion, as by joining or bringing together some or all of its dispersed particles through coalescence or agglomeration in situ in the continuous phase material and/or by electrophoresing such particles toward one or the other of the boundaries of the treating space where they may join with other particles that have earlier reached such boundary by electrophoretic or other action.

Another object of the invention is to discharge a charged stream into a space within an electrically insulated electrode free of connection to any external source of potential and free of any grounded or other electrode to which the charge of the stream might largely leak, all to the end that the charge imparted to the electrode will be maximized. The insulated electrode may be of various shapes with its internal space substantially cylindrical, frusto-conical, spherical or of other geometrical configuration. The voltage gradients between this electrode and the spaced companion electrode may be substantially uniform or may be nonuniform in some or all locations. In one embodiment of the invention it is an object to provide in an electric treater a treating space between substantially spherical electrodes maintained at different potential to establish therebetween an electric field of substantially uniform voltage gradient throughout.

The invention also comprises novel combinations and arrangements of parts and steps which will more fully appear in the course of the following description. The drawing merely shows and the description merely describes preferred embodiments of the present invention which are given by way of illustration or example.

In the drawing:

FIG. 1 is a vertical sectional view of one form of the electric treater of the invention shown in enlarged scale relative to its connected elements; and

FIGS. 2, 3, 4, and 5 are similar vertical sectional views of alternative forms of the electric treater.

The treater 9 of FIG. 1 includes an outer shell 10 and an inner shell 11 which function as electrodes defining a treating space 12 therebetween. In the embodiment illustrated, the shells 10, 11 are hollow and substantially spherical with the outer shell 10 grounded and with the inner shell 11 carried on an insulator 13 and a bracket 14 positioned in a collecting pocket 15 of the outer shell 10.

An inlet pipe 16 is attached to a flange of the outer shell 10 and may include an inner section 17 made of metal or insulating material and discharging into the interior of the inner shell 11. A pump 19 in a line 20 moves the fluid to be treated through the inlet pipe into the interior of the shell 11, then into the treating space 12 between the shells, into the well 15 and out through a line 21 as indicated by the arrows shown. Dispersed-phase material separating in the treater will collect in the bottom thereof and can be withdrawn intermittently or continuously through a pipe 22 having a valve 23. If desired any conventional level-responsive means 24 can be operatively connected to the valve 23 to maintain constant the level of the interfacial zone between the oil and the separated material within the treater.

Means are provided in the inlet line for generating a charge in the incoming fluid. Typically the charge generating means may comprise a charge generating element 25 mounted in the inlet pipe 16 adjacent the outlet end thereof. The charge generating element may be composed of a single tube, a bundle of capillary tubes, a pack or mass of material with many flow channels of small cross-sectional area such as glass wool or sintered bronze, or the like. The charge generated in a fluid flowing through such an element is approximately proportional to nL/d where n is the number of flow channels, L the length of a flow channel, and d the diameter of a flow channel.

In the operation of the treater, the electric charge generated in the fluid passing through the charge generating element is transferred to the inner shell 11 by contact of the charged fluid with the shell or some element electrically connected thereto. A potential difference is thus developed between the charged shell 11 and the grounded shell 10 producing an electrostatic field in the treating space 12. If desired a charge transfer means electrically connected to the inner shell can be employed to assist the charge transfer from the fluid to the inner insulated electrode. One or more wires across the interior of the shell 11 with their ends connected thereto will serve this function or a conducting open-pore maze 26 of conducting filaments, e.g. a very loose steel-wool-like mass, can be employed. Its open pores permit the charged fluid to flow therethrough in a path determined by the internal space geometry of the inner shell 11.

Flow of the fluid to be treated, here the effluent from the interior of the shell 11, through the treating space 12 between the shells results in electric treatment of the fluid in the same manner as occurs in conventional electric treaters. The particles in the dispersion are coalesced or agglomerated into larger particles which are more easily separated within the treater or which are in a better condition for later separation. Alternatively or in addition, some of the dispersed particles may electrophorese toward one or both of the electrodes to deposit thereon, joining with other particles during the electrophoretic movement thereof or at the time of deposit.

It is desirable that at least some separation of the coalesced agglomerated or electrophoresed material should take place in the treater thus far described. Such materials settling or dropping to the bottom of the shell

10 can be removed therefrom through the valved pipe 22. In some instances separation can be completed outside the treater, as by connecting the pipe 21 to a separator 28 for separation of the residual modified particles in the treated stream. The separator may be a settling chamber, a centrifuge, another electric treater, a chemical treater, or a combination thereof. For example, electrodes 29 and 30 of any known configuration may be insulated from each other in the separator 28, as indicated by dotted lines, and may be energized from any external source of potential 31 to establish a high voltage field therebetween, as in conventional electric treaters. A suitable chemical aiding such electric treatment or separation of the phases may be proportioned into a side pipe 32 and mixed with the stream entering the separator 28. The purified fluid or lighter phase material may be withdrawn from the top of the separator through a line 34 and the separated particles or heavier phase material may be withdrawn from the bottom of the separator through another line 35. If separation beyond the treater 9 is not needed or desired opening of a valve 36 in a by-pass line 37 will permit the effluent from the treater to by-pass the separator 28.

In some instances it is desirable to use the treater 9 to supplement earlier treatment of the dispersion or to preliminarily treat the dispersion in other equipment to condition it for the above-described treatment. Thus the incoming dispersion may be diverted to a container 40 by closing a valve 41 in the line 20 and opening a valve 42 in an inlet line 43 of the container. The dispersion can be preliminarily settled in the container 40 with some of the dispersed phase material being withdrawn through a valved pipe 44 and with the remaining dispersion conducted by a pipe 45 from the top of the container to the pipe 20 for later treatment in the equipment previously described. Spaced electrodes 47 and 48 energized from a high-voltage source of potential 49 may be employed in the container 40 to aid separation therein and condition the dispersion for its later treatment. For example if the dispersion entering the pump 19 is of a conductivity too high for best treatment in the treater 9 this conductivity can be reduced in the container 40. The treater 9 functions best with entering dispersions of a conductivity of about $5 \times 10^{-10} - 1 \times 10^{-12}$ mho/cm.

An alternative form of the treater 9' is shown in FIG. 2, wherein elements corresponding to those of FIG. 1 are identified by corresponding primed reference numerals. In the structure of FIG. 2, the charging liquid is separate from the fluid being treated with the latter being introduced directly into the treating space 12' via the line 20' and a perforated ring pipe 50. The charging liquid is circulated by a pump 52 via a line 53 into the inlet pipe 16'. The liquid then flows through the charging element 25' and into the inner shell 11' where its charge is transferred to the inner shell. The liquid is then withdrawn through another line 54 for recirculation. A supplementary insulator ring 55 may be employed to join the inner shell 11' to a skirt 56 separating the two materials and guiding the recirculated charging liquid to the line 54.

The treater of FIG. 2 permits operation with the dispersion to be treated being pumped at an optimum velocity for treating and with the charging liquid being pumped at an optimum velocity for charge generation transfer, which may be substantially different from the best velocity for the dispersion. Also, this arrangement permits use of a liquid having optimum charge generation and transfer characteristics as well as a clean liquid which reduces the tendency to clog the charge generating element. The charge carrying liquid can be a homogeneous or relatively pure liquid of relatively high electrical resistivity or it may carry particles as a dispersed phase such as water to increase the charging current. It should be substantially free of solids of large particle size. It should preferably have a resistivity within the range of about $5 \times 10^{-10} - 1 \times 10^{-12}$ ohm cm. Various hydrocarbons can be used as

the charging liquid, e.g. kerosene, jet fuel, n-heptane, etc. The charge induced by triboelectric action in the liquid passing through the charge generating element of either embodiment is largely the result of friction flow through appropriate passages. Such charge is dependent upon the number, size and length of the flow passages, as mentioned above, and the charge density in the stream is also a function of the velocity thereof in such flow passages. Utilizing glass wool as the charging element and flowing therethrough an oil having a conductivity of about 10^{-12} mho/cm. it is relatively easy to produce a potential on the inner shell or electrode 11 or 11' as high as 15 kv. or more. The charged stream should remain in this electrode or collector for a time sufficient for a substantial portion or substantially all of the charge of the stream to be transferred to the electrode. Circulation of the stream in contact with the inner surface of the electrode and/or the charge transfer means 26 or 26' within the electrode is desirable as facilitating this charge transfer. If the residence time of the stream in the electrode or collector is substantially longer than the relaxation time (about .18 second for oils of a conductivity of about 10^{-12} mho/cm.) it is assured that nearly all of the charge is transferred to the electrode. For a spherical electrode of an internal diameter of 20 cm. such an oil would need flow through the unit at a rate less than about 300 gal./min. Flow rates in the treating space 12 or 12' less than this are desirable and thus will insure that most or all of the charge of the stream will be imparted to the electrode.

The actual potential of the electrode thus charged will depend on the rate at which charges are transferred therefrom to the charged stream and the rate at which charges leak therefrom through the insulation and through the dispersion occupying the treating space 12 or 12'. It is desirable to minimize leakage through the insulation by providing insulators of the highest possible resistivity. The charges leaking through the dispersion to the outer grounded shell 11 are determined by the resistivity of the dispersion in the condition in which it exists in the treating space 12 or 12'. With inner and outer spherical electrodes respectively of 20 cm. and 24 cm. diameter and with a dispersion of a conductivity of about 10^{-12} mho/cm. (a resistivity of 10^{12} ohm cm.) the resistance of the dispersion in the treating space will be about $.36 \times 10^{11}$ ohm, which for a potential difference of 15 kv. between the electrodes will produce a leakage current through the dispersion of about $.4 \times 10^{-6}$ amps. A current of this magnitude is easily generated with a glass wool charging element.

In practice the voltage gradient across the treating space 12 or 12' will desirably be in the range of 1-25 kv./in. for best electric treatment. The voltage on the inner shell 11 necessary to produce such gradients will be determined by the spacing of the shells, which can vary from a small fraction of an inch to ten inches or more.

The invention is not well adapted to the treatment of dispersions of relatively high conductivity, particularly the embodiment of FIG. 1, as these tend to reduce the treating potential of the inner shell by dissipating the charge of the inner shell 11 more rapidly than it can be renewed by the charged stream. However treatment of dispersions of resistivities of 5×10^{10} ohm cm. and greater are within the scope of the invention.

Flow through the treating space 12 or 12' between substantially spherical electrode elements is exceptionally smooth and nonturbulent, irrespective of how the potential difference therebetween is developed, leading to excellent electric treatment of the dispersion. Edge effects or zones of extreme non-uniform gradient are minimized or eliminated so that the dispersion is subjected to an electrostatic field of uniform voltage gradient measured between the electrodes at substantially all positions within the treating space.

However the use of electrostatic fields of uniform voltage gradient throughout is not essential to the invention.

In some instances some non-uniformity of the field is desirable. Electric fields of somewhat different pattern with portions of nonuniform gradient can be obtained by use of the embodiments of the invention shown in FIGS. 3, 4 and 5.

Referring to FIG. 3, the outer shell 110 is a generally cylindrical container while the inner shell 111 is a smaller cylinder closed at its top and open at its bottom. An annular treating space 112 is formed therebetween. The inner shell 111 is hung from an insulator 113 disposed in a pocket 115. An inlet pipe 116 with an inner section 117 is fed by a pump 119 through a line 120. The dispersion flows upward within the inner shell 111, downward in laying contact with the inner surface thereof, outward beneath the lower lip thereof and upward in the annular space 112 to discharge through an outlet line 121. A charge generating element 125 of the type previously described is positioned partly in the inlet pipe 116 and partly in its inner section 117 and terminates short of the upper open end of the latter, an arrangement which can also be employed in the embodiments of FIGS. 1 and 2 if desired.

The space within the inner shell 111 may be open or may contain the open-pore charge-transfer means previously described. The charge induced on the dispersion 25 when passing through the charge generating element 125 is transferred to the inner shell 111 acting as a collector and as an inner electrode establishing the high-voltage electric field in the annular treating space 112 in which the dispersion is treated. There is little or no settling of the dispersed material except when the dispersion passes beneath the lower edge of the inner shell 111 and rises in the annular treating space 112. Settled dispersed material is withdrawn through a valved pipe 122. The field pattern is distinctly non-uniform in zones adjacent the top and bottom edges of the inner shell 111, as suggested by the diverging lines 123 and 124. Particularly in the later zone the dielectrophoretic forces aid in the resolution of the dispersion, tending to retain the dispersed-phase material in the vicinity thereof and increasing the coalescing action.

The treater of FIG. 4 is generally similar to FIG. 3 and has corresponding parts designated by corresponding primed numerals. The inner shell 111' is here frustoconical in shape but has its lower edge turned inwardly at 45 125 to provide a throat 126 through which the charge dispersion moves downward before rising around the inner shell. The treating space 112' is here of increasing width toward the top, providing a tapered field effect. The zones of nonuniform gradient, indicated by the radial lines 123' and 124' produce dielectrophoretic forces aiding the coalescence. The zones in which such fields are established are generally circles of revolution about the vertical axis of the treater. The field intensities therein are somewhat higher than in the main portions of the annular 50 treating space 112' either because of closer electrode spacing or electrode curvature of the inner shell 111'. These field intensities should not be high enough to redisperse the dispersed-phase masses produced in other regions of the annular treating space 112' nor sufficient to cause excessive current drain which would tend to dissipate the transferred charge on the inner shell 111' too rapidly.

The embodiment of FIG. 5 employs an outer shell 210 shaped as a horizontally disposed cylinder. An inner shell 211, also generally cylindrical, is disposed therein to provide an annular treating space 212 therebetween. The inner shell is supported by two insulators 213 positioned respectively in pockets 215. An inlet pipe 216 has an inner section 217 discharging into the interior of the inner shell 211. A pump 219 can supply the dispersion to the inlet pipe 216 through a line 220. In this event the dispersion charged by the charge generating element 225 discharges leftward and then rightward in laying relationship with the inner wall of the inner shell 211 to impart its charge thereto. The dispersion then flows through 70 a mouth 226 and is electrically treated during leftward

flow along the annular treating space 212. Separation of dispersed-phase material takes place during this flow, the effluent oil discharging through a line 221 while the separated dispersed-phase material is withdrawn from a collocated body thereof through a valved pipe 222. Dielectrophoretic zones are indicated by the radial lines 224 and 227, the treater thus operating in a manner similar to the treaters of FIGS. 3 and 4 except that the coalesced masses of the dispersed-phase material move circumferentially downward rather than axially downward in the treating space.

In the embodiment of FIG. 5, as in the other embodiments, it is sometimes possible to divide the incoming stream of dispersion, using a portion thereof for the electrode-charging function and discharging another portion thereof directly into the treating space between the inner and outer shells. Thus by opening a valve 230 a portion of the pumped dispersion can enter a distributor 231 extending along the bottom of the treating space 212 above the body of separated material. This distributor may be any multi-orifice pipe or pipe network discharging smaller streams of the dispersion at different horizontally-spaced positions below the level of the inner shell 211. The material of the streams can thus rise circumferentially through the treating space 212 while being displaced axially due to the flow of the charging portion of the stream. The treated oil is withdrawn through the pipe 221 as before. An effective electric treatment of the composite stream results.

In FIG. 5, as in the other embodiments, it is also possible to increase the volume and thus the velocity of the dispersion flowing through the charge generating element 225 by returning to the influent stream a portion of the effluent stream from the pipe 221. The by-passed portion of the effluent stream can flow through a pipe 249 by opening a valve 241 and can enter the pipe 220 ahead of the pump 219. This dilutes and augments the volume of the incoming dispersion and can be made to increase the charge transferred to the inner shell 211. In FIGS. 4 and 5 charge transfer from the stream to the inner shell 40 can be facilitated by use of the open-pore charge-transfer maze described with reference to FIGS. 1 and 2.

The treaters as embodied in FIGS. 3, 4 or 5 can be connected with the pre-treating or post-treating arrangements of FIGS. 1 and 2. In this way the influent streams to such treaters can be conditioned for better treatment or the effluent streams from such treaters may be subjected to further treatment.

As an example of the invention, a jet fuel after being washed with an aqueous solution and while containing a few tenths of a percent of dispersed phase material can be flowed through a glass wool charging element in an inlet pipe of about .5-1.0 cm. internal diameter into a thin walled inner shell 11 of 20 cm. internal diameter and thence through the treating space provided within an outer shell 10 of 24 cm. internal diameter, FIG. 1 embodiment, at a rate of about 0.5-1.0 gal./min. Depending on the flow rate and the insulator leakage the inner shell 11 will be maintained at a potential of about 2-20 kv. above ground potential which at an electrode spacing of slightly less than 2 cm. will subject the dispersion to a field of a gradient of about 1-10 kv./cm. or about 2.5-25 kv./in. inducing coalescence of the dispersed particles and some electrophoretic deposition thereof on the shells. The treated effluent will be found to contain somewhat less dispersed phase material, typically a few hundredths of a percent, the reduction from the entering stream representing the portion of the dispersed material separated within the treater. The fuel effluent upon gravitational settling in the separator 28 will produce an upper effluent containing less than .01% residual dispersed aqueous material.

It should be recognized however that the invention can also be used as an aid to other electric or chemical treating-separating processes and need not be used to

produce the ultimate product desired. Thus high-voltage energization of one or both of the electrodes 29, 30 in the separator 28 and subjecting the entering already-treated stream to the action of the one or more resulting electric fields can be used to reduce the content of dispersed aqueous material in the upper effluent through line 34 to negligible values, usually below .001%. If the separator 28 and its electrodes are of the type suggested in the patent to Stenzel, No. 2,853,356, or in the application of Stenzel and Turner, Ser. No. 230,978, now Patent No. 3,295,160, entitled Electric Treater for Dispersions, the upper effluent will contain even less residual dispersed material, often less than .0005%. In all instances where the treater 9 or 9' is used ahead of another electric treater it acts to condition the dispersion for the ultimate electric treatment and make same easier or more effective. There are also many advantages in passing the influent stream through a preliminary electric treater such as provided at 40, 47, 48 and 49 before entering the self-energizing treater 9 or 9'.

Although exemplary embodiments of the invention have been disclosed and discussed, it will be understood that other applications of the invention are possible and that the embodiments disclosed may be subjected to various changes, modifications and substitutions without necessarily departing from the spirit of the invention.

We claim as our invention:

1. In an apparatus for electrically treating a hydrocarbon-continuous dispersion comprising a hydrocarbon phase with dispersed particles therein, the combination of:

means for generating an electrical charge in a stream of fluid to produce a charged stream;
a first electrode;
a second electrode spaced from said first electrode defining a treating space therebetween;
means for mounting said first electrode electrically isolated and insulated from said second electrode;
means for flowing said charged stream of fluid into electrical contact with said first electrode to transfer thereto the charge of said stream and establish an electrostatic field in said treating space;
means for delivering a stream of said dispersion to one portion of said treating space; and
means for withdrawing treated dispersion constituents from said treating space.

2. In an apparatus for electrically treating a hydrocarbon-continuous dispersion comprising a hydrocarbon phase with dispersed particles therein, the combination of:

an apertured charge generating element for generating an electrical charge of high voltage in a fluid passing therethrough;
a first electrode;
a second electrode spaced from said first electrode defining a treating space therebetween;
means for mounting said first electrode electrically isolated and insulated from said charge generating element and said second electrode;
means for flowing a stream of fluid through said charge generating element to impart a charge thereto and thence promptly into electrical contact with said first electrode to induce a charge thereon and establish a high-voltage electrostatic field in said treating space; and
means for delivering a stream of said dispersion to one portion of said treating space for electric treatment therein.

3. In an apparatus for electrically treating a hydrocarbon-continuous dispersion comprising a hydrocarbon phase with dispersed particles therein, the combination of:

means for generating a high-voltage electrical charge in a fluid passing therethrough;
a first hollow electrode;
a second hollow electrode spaced from said first electrode defining a treating space therebetween;

means for mounting said first electrode electrically isolated and insulated from said second electrode; means for flowing said charged stream of fluid into said first electrode into electrical contact therewith to impart a charge thereon and establish a high-voltage electrostatic field in said treating space; and means for delivering a stream of said dispersion to said treating space for treatment therein.

4. An apparatus as defined in claim 3 in which said first hollow electrode is within and concentric with said second hollow electrode, said first electrode providing a central cavity closed except for an opening therethrough, said charge-generating means including a conduit of smaller size than said opening discharging said charged stream into the interior of said first electrode through said opening, there being an annular exit space within said opening around said conduit conducting said fluid from the interior of said first electrode.

5. Apparatus as defined in claim 3 including one or more conducting filaments within and electrically connected to said first hollow electrode in the path of said charged stream to aid in transferring to said first electrode the electrical charge of such stream.

6. In an apparatus for electrically treating a hydrocarbon-continuous dispersion comprising a hydrocarbon phase with dispersed particles therein, the combination of:

a charge generating element for generating an electrical charge in a fluid passing therethrough; a first hollow electrode; a second hollow electrode spaced from said first electrode defining a treating space therebetween; means for mounting said first electrode electrically isolated and insulated from said second electrode; means for circulating a stream of said fluid in a closed path through said charge generating element and first electrode to impart a charge on said first electrode and establish an electrostatic field in said treating space; and means for flowing a stream of said dispersion through said treating space in spaced relation with said circulating fluid.

7. In an apparatus for electrically treating a hydrocarbon-continuous dispersion comprising a hydrocarbon phase and a dispersed phase comprising particles dispersed in the hydrocarbon phase, the combination of:

a charge generating element for generating an electrical charge in a fluid passing therethrough; a first hollow electrode; a second hollow electrode concentric with and spaced from said first electrode defining a treating space therebetween; means for electrically isolating and insulating said first electrode from said charge generating element and said second electrode; means for flowing a stream of said dispersion through said charge generating element and into said first electrode to impart a charge thereon and establish an electrostatic field in said treating space; means for delivering the stream of said dispersion from said first electrode to one portion of said treating space; and means for withdrawing treated dispersion constituents from said treating space.

8. In an apparatus for electrically treating a hydrocarbon-continuous dispersion comprising a hydrocarbon phase and a dispersed phase comprising particles dispersed in the hydrocarbon phase, the combination of:

a charge generating element for generating an electrical charge in a fluid passing therethrough; a first hollow electrode; a second hollow electrode concentric with and spaced from said first electrode defining a treating space therebetween; means for electrically isolating and insulating said first

5 electrode from said charge generating element and said second electrode; means for dividing a stream of said dispersion into two stream portions; means for flowing one stream portion through said charge generating element, into said first electrode and from an exit portion thereof to impart a charge on said first electrode and establish an electrostatic field in said treating space; means for delivering the dispersion from said exit portion to said treating space; means for delivering the other stream portion to said treating space, the electrostatic field in said treating space treating both stream portions; and means for withdrawing treated dispersion constituents from said treating space.

9. In an apparatus for electrically treating a hydrocarbon-continuous dispersion comprising a hydrocarbon phase and a dispersed phase comprising particles dispersed in the hydrocarbon phase, the combination of:

a charge generating element for generating an electrical charge in a fluid passing therethrough; a first hollow electrode; a second hollow electrode concentric with and spaced from said first electrode defining a treating space therebetween; means for electrically isolating and insulating said first electrode from said charge generating element and said second electrode; means for flowing a stream of said dispersion through said charge generating element and into said first electrode to impart a charge thereon and establish an electrostatic field in said treating space; means for delivering the dispersion from the interior of said first electrode to said treating space, the electrostatic field in said treating space treating the dispersion to bring together at least some of the dispersed particles and produce a treated hydrocarbon; means for removing a stream of said treated hydrocarbon from said treating space; and means for returning a portion of such removed treated hydrocarbon to said stream of dispersion flowing through said charge generating unit to augment the volume thereof.

10. Apparatus for electrically treating a hydrocarbon-continuous dispersion comprising a hydrocarbon phase with a dispersed phase of particles therein, said apparatus including:

an outer hollow electrode having a substantially spherical inner surface; an inner isolated electrode having a substantially spherical outer surface; electrical insulation means for mounting said inner electrode within said outer hollow electrode with said substantially spherical surfaces concentric and spaced from each other to provide a treating space therebetween, said treating space having entrance and exit portions spaced diametrically from each other; means for developing a potential difference between said electrodes establishing an electrostatic field in said treating space; means for delivering a stream of said dispersion to said entrance portion for treatment in said treating space during flow therewith; and means for conducting a stream of treated dispersion from said exit portion of said treating space.

11. A method of electrically treating a hydrocarbon-continuous dispersion comprising a hydrocarbon phase with dispersed particles therein, in a space defined by first and second electrodes and in the absence of potential applied between said electrodes by any external source of potential connected thereto, to join the dispersed particles together, including the steps of:

producing an electrically charged fluid stream;

flowing the charged stream into electrical contact with the first electrode to impart a charge thereon and establish an electrostatic field in the space between the electrodes; 5 delivering a stream of the dispersion to said space; and withdrawing treated dispersion constituents from said space.

12. A method of electrically treating a hydrocarbon-continuous dispersion comprising a hydrocarbon phase with dispersed particles therein, in a space defined by first and second electrodes and in the absence of potential applied between said electrodes by any external source of potential connected thereto, to bring together the dispersed particles, including the steps of: 10 producing an electrical charge of high voltage in a stream of the dispersion;

flowing the charged dispersion stream into electrical contact with the first electrode to impart a high-voltage charge thereon and establish a high-voltage electrostatic field in the space between the electrodes; then flowing the dispersion stream into said space; and withdrawing treated dispersion constituents from said space.

13. A method of electrically treating a hydrocarbon-continuous dispersion comprising a hydrocarbon phase with dispersed particles therein, in a space defined by first and second electrodes, to bring together the dispersed particles into larger particles, including the steps of:

producing an electrically charged fluid stream in a charging zone; 20 moving the charged fluid stream into electrical contact with the first electrode to transfer thereto the charge of such stream and establish an electrostatic field in the space between the electrodes; returning the discharged stream to said charging zone for recharging and for production of said charged fluid stream; 30 delivering a stream of the dispersion to be treated to the space between the electrodes; and withdrawing treated dispersion constituents from said space.

14. A method of electrically treating a hydrocarbon-continuous dispersion comprising a hydrocarbon phase with dispersed particles therein, in a space bounded by a first insulated electrode and a second grounded electrode and in the absence of potential applied between said electrodes by any external source of potential connected thereto, said method including the steps of:

inducing electrostatic charges in a fluid stream by flowing same through a porous mass to produce a charged fluid stream;

flowing the charged stream into electrical contact with said first electrode and maintaining this contact for a period of time sufficient to transfer a substantial part of the charges to said first electrode to charge same to a dispersion-treating potential above ground potential, thereby establishing an electrostatic field in the space between said electrodes;

flowing a stream of the dispersion to be treated into said space in bridging relationship with the electrodes for treatment of the dispersion during advancement along said space, some of the charge of said first electrode leaking through the dispersion in said space to the second electrode as a function of the resistivity of the dispersion bridging said electrode; and

controlling the charge and rate of flow of said fluid stream with relation to the resistivity of the dispersion

bridging said electrodes to maintain said first electrode at a dispersion-treating potential above ground potential.

15. A method of electrically treating a hydrocarbon-continuous dispersion comprising a hydrocarbon phase with dispersed particles therein by use of an electrode insulated from ground but free of connection to any external source of potential, said method including the steps of:

flowing in charge-transfer relation with one portion of said electrode an electrically charged stream in a manner to transfer a substantial portion of the charge of such stream to said electrode and develop an electrode potential above ground potential; flowing in contact with another portion of said electrode a stream of said hydrocarbon-continuous dispersion; and

controlling the charge of said charged stream and its time of contact with said electrode relative to the resistivity of said dispersion to maintain said electrode at a potential to establish an electrostatic field in the stream of hydrocarbon-continuous dispersion sufficient in intensity to separate at least some of the dispersed particles of such dispersion.

16. A method as defined in claim 15 including the steps of separating some of the treated dispersed particles of the dispersion in said electrostatic field to produce a treated dispersion containing residual dispersed particles, and subjecting said residual dispersion to additional treatment to separate additional dispersed particles therefrom.

17. A method of electrically treating a hydrocarbon-continuous dispersion comprising a hydrocarbon phase with a dispersed phase therein comprising dispersed particles, which method involves the use of an electrode insulated from ground but free of connection to any external source of potential, said method including the steps of:

removing larger dispersed particles from said dispersion;

flowing the resulting dispersion through a large number of passages at sufficient velocity to induce a charge on the dispersion;

flowing the charged dispersion in charge-transfer relation with said electrode to transfer a substantial portion of the charge of such stream to said electrode and develop an electrode potential above ground potential;

employing said electrode potential to establish a high-voltage electrostatic field;

flowing the stream of dispersion after such charge transfer into said electrostatic field for treatment therein; and

controlling the charge on the charge dispersion stream and the time of charge transfer to said electrode relative to the resistivity of said dispersion in said electrostatic field to maintain said electrode at a potential sufficient to bring together at least some of the dispersed particles of such dispersion in such field.
